UNITED STATES PATENT OFFICE.

GUSTAF L. LUNDIN, OF NEW BEDFORD, MASSACHUSETTS, ASSIGNOR TO NASHAWENA MILLS, OF NEW BEDFORD, MASSACHUSETTS, A CORPORATION OF MASSACHUSETTS.

LOOM HARNESS.

Application filed May 19, 1925. Serial No. 31,307.

The present invention relates to an improvement in loom harnesses, and more particularly to harnesses for doup weaving.

The object of the invention is to produce an improved doup harness, and to this end the invention consists in the harness hereinafter described and particularly defined in the claims.

In the accompanying drawings illustrating the preferred form of the invention, Fig. 1 is an elevation showing a standard harness provided with a heddle, and a doup harness provided with a doup, one heddle and doup only being shown for the sake of clearness; Fig. 2 is a section taken on the line 2—2, Fig. 1; Figs. 3, 4 and 5 illustrate relative positions of the crossing harnesses; and Figs. 6 and 7 illustrate a modified form of the invention.

The illustrated embodiment of the invention is described as follows: The standard harness has the usual frame 1 and shafts 2 for the heddles. These heddles are made of wire, and the eye 3 is formed in the usual manner except that it occupies an inclined position, as shown in Fig. 1. Above the standard eye 3 is the long doup eye 4, formed in the same heddle for a purpose presently to be described. The doup harness 5 is provided with a bottom shaft 6, which carries the link 7. To the upper end of this link is attached the doup or doup needle 8. The doup consists of a wire bent upon itself and more or less stiff and self supporting, and having its two ends threaded over the link 7. The doup 8 is threaded through the standard heddle by extending one leg through the doup eye 4, and thence down through the standard eye 3, after which both attaching loops 9 in the ends of the doup needle are threaded over the leg 10 of the link; after this the link is sprung over the shaft 6. It will be observed that the one leg 10 of the link 7 is a straight leg, and that the other leg 11 is provided with a hook 12 at its end, which is adapted to engage the under side of the doup shaft 6.

In the drawings the crossing threads are indicated by the reference characters 13 and 14, and the doup thread is indicated by the reference character 15.

It is to be observed that the top and bottom loops of the standard heddle which embrace the shafts 2 of the standard harness

determine the position of the heddle in the harness and that the doup eye lies in the same plane as the top and bottom loops of the heddle. The standard eye lies in a plane inclined sidewise to the plane of the doup eye. This construction supports the standard heddle in such a position that the doup freely moves through the doup eye and standard eye, and the loop formed between the upper side of the standard eye and the upper end of the doup (see Fig. 1) lies in a plane transverse to the loom so that the doup thread may move freely and any bends in the doup thread are avoided. It is also to be observed that the loop in the upper end of the doup which embraces the doup thread lies in the same plane as the loops 9 at the ends of the doup wire so that the upper end of the doup wire normally occupies a position generally transverse to the warps.

Heretofore the doup eye of a standard heddle has been a short eye, and in the operation of the loom it has sometimes occurred that the doup would strike the upper end of the doup eye, thereby straining the parts and tending to push the doup harness out of place, as well as to interfere with the movements of the parts. One feature of the invention consists in the employment of a doup eye of such length that irrespective of the relative movements of the standard and doup harnesses, the doups will never strike the top of the doup eye.

In former practice the standard eye has lain in the plane of the wires of which it was formed. This caused the bending of the doup in the operation of the loom, and added difficulties in weaving, and increased the wear of the parts. Moreover, the eye formed by the doup where it projects through the standard eye had a very tapering bottom, which caused it to pinch the doup thread. In the present construction the bottom of this eye for the doup thread is much less liable to pinch the doup thread.

The connection of the doup to the doup harness by means of a lost motion link is another feature of advantage in this construction, inasmuch as it permits the relative movement of the doup harness and doup. Thus referring to Fig. 3, we see the parts in the position in which they are shown in Fig. 2, with the doup shaft 6 at the bottom of the link 7. In the next position shown

in Fig. 4, the standard is lowered and the dousp drop, the link sliding down on the dousp shaft 6 and permitting non-interference of the dousp with the crossing threads. In Fig. 5 the dousp thread is shown in lowered position, and the link 7 as resting on the shaft 6. The capacity of the dousp to adjust itself by reason of this lost motion connection with the dousp harness contributes materially to the good operation of the mechanism by avoiding the interference of the dousps with each other and reducing the upward motion of the dousp when not lifted by the dousp thread or end while still maintaining the same vertical movement of the dousp harness itself.

In Figs. 6 and 7 the standard 16 and the dousp 17 are both made of thin resilient sheet metal, conveniently of the sort that steel heddles and drops are made of. The link 18 is also made of a sheet metal stamping. The ends of the dousp are slotted and nest together as shown. The standard eyes 19 and the dousp eye 20 afford large clearances affording free relative movements of the parts. This form of the invention commends itself by reason of the compactness with which elements may be assembled.

Having thus described the invention, what is claimed is:—

1. A harness for dousp weaving comprising a standard having a heddle provided with an inclined eye and a long dousp eye above it, a dousp harness, a dousp passing through the dousp eye and standard eye, and

a lost motion connection between the dousp and the dousp harness.

2. A harness for dousp weaving having, in combination, a standard having a heddle provided with a standard eye and a dousp eye, a dousp harness having a dousp passing through the dousp eye and the standard eye, and a dousp link for connecting the dousp to the dousp harness having provision for permitting lost motion between the dousp and its harness. 40 45

3. A harness for dousp weaving having, in combination, a standard provided with a heddle having a standard eye and a dousp eye, a dousp harness, a dousp passing through the dousp eye and standard eye, the dousp being provided with fastening loops at its ends, a dousp link consisting of an elongated member passed through the loops in the ends of the dousp and embracing a portion 50 55 of the dousp harness, said link being open at one point for application to and removal from the dousp harness.

4. A harness for use in dousp weaving having, in combination, a standard provided with a heddle having a standard eye and a dousp eye, a dousp harness, a self supporting dousp passing through the dousp eye and standard eye of the standard, and having lost motion connection with the dousp harness. 60 65

In testimony whereof I have signed my name to this specification.

GUSTAF L. LUNDIN.
